UNITED STATES PATENT OFFICE.

JOSEPH BERGER, OF UTICA, NEW YORK, ASSIGNOR TO UNION SPECIAL MACHINE COMPANY, OF CHICAGO, ILLINOIS, A CORPORATION OF ILLINOIS.

TRIMMING MECHANISM FOR SEWING MACHINES.

Application filed February 25, 1926. Serial No. 90,605.

The invention relates to new and useful improvements in a trimming mechanism for sewing machines.

An object of the invention is to provide a trimming mechanism which may be adjusted bodily as a unit toward and from the stitching mechanism for varying the width of the edge to be covered by overseaming stitches, which unit trimming mechanism is rigidly secured to the bed plate of the machine when in its adjusted positions.

In the drawings which show by way of illustration one embodiment of the invention—

15 Figure 1 is a view partly in front elevation and partly in section showing a portion of a sewing machine with my improved trimming mechanism unit applied thereto;

20 Fig. 2 is a sectional view on the line 2—2 of Fig. 1;

Fig. 3 is a perspective view of the unit supporting means detached from the machine, also showing the cover plate which is attached thereto, and

25 Fig. 4 is a view partly in plan and partly in section of the machine immediately above the throat plate and the trimming mechanism unit.

In my co-pending application Serial No. 30 729,100, filed July 30, 1924, I have shown, described and claimed in detail the trimming mechanism which is present in this application. The present invention is directed to the unit mounting of the parts of the trim-

35 ming mechanism on the bed plate of the machine, so that it can be adjusted toward and from the stitching mechanism. The sewing machine to which the invention is applied

40 consists of a needle 1, an under thread carrying looper 2, and an overedge thread carrying looper 3. These stitching elements co-operate to form overedge stitches. The material is fed to the stitching mechanism by feed dogs 4 which operate through slots in a

45 throat plate 5. This throat plate 5 is rigidly secured to an upstanding member 6 carried by a bed plate 7. The throat plate is secured by screws 8, 8 to this upstanding member 6.

The trimming mechanism consists of a stationary trimming blade 9 and a movable trimming blade 10. This movable trimming blade 10 is carried by a bracket arm 11 fixed to a shaft 12. The shaft 12 is mounted in a bracket 13. Said bracket 13 is provided with

55 a depending tenon or rib 14 which is adapted

to engage a similarly shaped groove 15 formed in the bed plate 7 of the machine (see Fig. 2). Said bracket 13 is secured to the bed plate by bolts 16, 16. These bolts 16, 16 pass through elongated slots 17, 17, 60 respectively. The slots 17 are formed in the bed plate, and the bolts are passed up through these slots in the bed plate, and are threaded into the bracket 13. The clamping plate 18 is provided, through which both of 65 the bolts pass, and this clamping plate is drawn tightly against the under face of the bed plate.

The shaft 12 carrying the bracket arm 11 supporting the movable trimming blade is 70 moved endwise and to the left as viewed in Fig. 1, by the spring 19. The shaft is rocked by an arm 20 to which is connected a link 21. The bracket 13 is provided with spaced sleeves 22, 22, and the shaft 12 is located in 75 these spaced sleeves. The arm 20 is secured to the shaft between the sleeves 22, 22, and there is sufficient play to permit a limited endwise movement of the shaft 12 through the action of the spring 19.

Secured to one end of the bracket 13 is an upstanding post 23. This upstanding post engages the under face of the throat plate 5. Said throat plate is provided with a slot 24 through which a screw 25 passes. The purpose of the slot is to permit the post to be adjusted with the bracket 13. The stationary blade 9 of the trimming mechanism is mounted on this post 23. The post 23 is secured to the bracket 13 by screws 26, 26. Attached to the front face of the bracket 13 is a cover plate 27.

The present invention is directed particularly to this unit trimming mechanism which consists of a unit support on which both the movable trimming blade and the stationary trimming blade are mounted. This unit support is capable of adjustment toward and from the needle in a direction at right angles to the line of feed. This adjustment can be 95 readily accomplished by loosening the bolts 16, 16, and also the screw 25. When these parts are loosened, then the entire trimming mechanism may be shifted as a unit toward and from the needle. The purpose of the adjustment is to vary the width of the edge of the fabric which is covered by the overseaming stitches. It will be noted that the trimming mechanism is carried by a unit support 100 which is mounted on the bed plate of the 105

machine, and therefore, the entire trimming mechanism has a rigid durable supporting means which can be readily shifted as noted above, for varying the width of the edge 5 which is covered by overseaming stitches.

The cover plate 27 is provided with a deflector 27^b which rests against the supporting ledge 27^a when the cover plate is closed. This positions the deflector relative to the trimming devices so that the trimmed off strip is deflected back toward the front of the machine and away from the stitching mechanism. Inasmuch as the cover plate is mounted on the unit supporting bracket 13 which carries the trimming members, it will readily be seen that when the trimming device is adjusted toward and from the needle of the stitching mechanism, the strip deflector is adjusted therewith.

20 While I have described the trimming mechanism as used in conjunction with an overseaming stitching mechanism, it will be understood that it may be used in connection with any character of stitching mechanism where it is desired to trim the edge of the material a given distance from the line of stitching.

It is obvious that minor changes in the details of construction may be made without departing from the spirit of the invention as set forth in the appended claims.

Having thus described the invention, what I claim as new and desire to secure by Letters Patent, is—

35 1. In a sewing machine, the combination of a bed plate, a throat plate, stitch forming mechanism including a needle, trimming mechanism including upper and lower trimming members, and means for supporting said trimming members including a bracket on which said members are mounted, means for connecting said bracket to the bed plate so that said bracket can be adjusted for varying the position of the trimming 40 mechanism relative to the needle and means for supporting one end of said throat plate on said bracket.

50 2. In a sewing machine, the combination of a bed plate, a throat plate, stitching mechanism including a needle, upper and lower trimming members, a bracket adjustably attached to the bed plate and capable of being adjusted toward and from the needle, an upstanding post carried by the bracket on 55 which is mounted said lower trimming member, said post being adjustably secured to the throat plate, and means whereby said

upper trimming member is mounted on said bracket.

3. In a sewing machine, the combination 60 of a bed plate, a throat plate, stitching mechanism including a needle, trimming mechanism including an upper movable trimming member and a lower stationary trimming member, a shaft carrying said upper movable member, a bracket in which said shaft is mounted, a post secured to said bracket on which said stationary trimming member is mounted, means for adjustably securing said bracket to said bed plate, and means for 65 adjustably securing said post to said throat plate whereby said trimming mechanism as a unit may be adjusted toward and from the needle.

4. In a sewing machine, the combination 70 of a bed plate, a throat plate, stitching mechanism including a needle, trimming mechanism including an upper movable trimming member and a lower stationary trimming member, a shaft carrying said upper movable member, a bracket in which said shaft is mounted, a post secured to said bracket on which said stationary trimming member is mounted, means for adjustably securing 75 said bracket to said bed plate, means for adjustably securing said post to said throat plate whereby said trimming mechanism as a unit may be adjusted toward and from the needle, said adjustable connection between the bed plate and the bracket including a rib on said bracket, a groove in said bed plate in which said rib fits, said bed plate having slots beneath said rib and groove, and bolts adapted to be passed up through 80 said slots and threaded into said bracket for holding the bracket in adjusted positions.

5. In a sewing machine, the combination 85 of a bed plate, stitch forming mechanism including upper and lower trimming members, means for supporting said trimming members whereby the same may be adjusted toward and from the stitching mechanism as a unit for varying the position of the trimming mechanism relative to the needle, a deflector hingedly mounted on said means for supporting the trimming members for deflecting the trimmed off strip, said deflector being adjustable with the trimming mechanism as a unit and capable of swinging to give access to the stitch forming mechanism.

In testimony whereof, I affix my signature.
JOSEPH BERGER.
